UNITED STATES PATENT OFFICE.

JOSEF HECHT AND CHARLES CIZENFELD, OF BALTIMORE, MARYLAND; SAID CIZENFELD
ASSIGNOR, BY MESNE ASSIGNMENTS, TO SAID HECHT.

FOUNTAIN-BRUSH.

1,217,597.

Specification of Letters Patent. Patented Feb. 27, 1917.

Application filed November 12, 1915, Serial No. 61,041. Renewed January 12, 1917. Serial No. 142,115.

To all whom it may concern:

Be it known that we, JOSEF HECHT and CHARLES CIZENFELD, citizens of the United States of America, residing at Baltimore, 5 in the State of Maryland, have invented certain new and useful Improvements in Fountain-Brushes, of which the following is a specification.

This invention relates to a bath brush of 10 the fountain type, which may be connected to either a faucet of the city water system or to any other source of supply.

One of the objects of this invention is to provide a brush which can be disassembled 15 and used as a shower.

Another object of this invention is to provide a brush which can be used with soap without the inconvenience of handling the soap and without waste.

20 Other objects of this invention will be set forth in the detailed description which follows.

To further illustrate our invention we have prepared drawings which fully illustrate the device in detail.

25 Referring to the drawings:

Figure 1 is a vertical sectional view of our brush with the upper part raised and the bottom part in engagement with the central 30 portion.

Fig. 2 discloses the brush assembled and with certain parts cutaway thereby disclosing soap within the receptacle formed by the upper and central portions of the brush, the 35 lower portion being disengaged from the spring clips of the central portion.

Fig. 3 discloses a modified form of central and lower portions of the brush carrying a sponge in place of the brush.

40 Referring to the drawings the numeral 5 designates a flexible connection, such as a rubber hose, which is adapted to be secured to the source of water supply. The numeral 6 designates a tubular member to which the 45 member 5 is connected. The upper portion of our device consists of a ring-shaped member 7 which is connected with the tubular portion 6 by a crown 8.

At the junction of the portions 7 and 8 50 there is inserted across the entire crown 8 a perforated member 9 which when the upper portion is used separately acts as a shower. Upon the ring 7, there is provided projections 10 which assist in rotating the 55 upper portion with relation to the central

portion of our device. The central portion of our device consists of a ring-like member 11, which has an inturned flange 12 and is provided near its lower edge with spring 60 clips 13. At its upper edge bayonet slots 14 are provided, the same acting as locking means for retaining the upper portion of our device in engagement with the central portion.

We provide a brush portion or as heretofore called the lower portion 15, which consists of a member adapted to retain bristles 16. This member 15, is provided with a rigid head piece 17, which is perforated as shown at 18.

70 The member 15 is also provided with perforations 19 which register with perforations 18.

In order that a better understanding of this invention can be had, we describe the 75 operation as follows:

The pipe 5 is attached to the source of supply and to the tubular member 6 and the brush assembled by dropping the upper portion of the device as shown in Fig. 1, into 80 the central portion and slightly turning so as to lock the parts together. Water will then flow through the brush as will be readily seen. If it is desired to use soap, the upper portion is released from the central portion and soap inserted therebetween 85 while the lower portion is separated from the central portion by releasing the spring 13. The lower portion will then be dropped so that the head 17 engages the inturned flange 90 12. This provides sufficient room for the reception of a cake of soap between the upper and central members. When the water is turned on and the brush used with a rotary motion, the brush portion will revolve 95 which will cause the soap to be slightly abraded by its engagement between the perforated member 9 and the head piece 17, which will result in a good lather. If it is desired to use the brush as a shower, the 100 central and lower portions are entirely removed.

We do not desire to limit ourselves to the specific construction here shown, as it will be understood that various changes in the 105 structural details may be made without a departure from the spirit and scope of the invention.

What we claim is:

A fountain brush comprising an upper 110

shower portion having an inlet at one end and an open ring at its opposite end, a perforated plate secured within said ring, a central connecting portion detachably secured around the said ring and having an inwardly extending annular flange, a cylindrical perforated lower portion revolvably and longitudinally movably mounted within the said flange, detachable spring clip sup-
5 porting means for the said lower portion outwardly carried by said central portion,

and a retaining perforated head piece upon said lower portion within the said central portion inwardly of said flange, a soap sudsing chamber being formed between said perforated plate and head piece when said lower portion is in its lowered position disengaged from said supporting means. 15

In testimony whereof we affix our signatures.

JOSEF HECHT.
CHARLS CIZENFELD.
